[57] CLAIM

The ornamental design for a bacteria filter or similar article, as shown and described.

DESCRIPTION

FIG. 1 is a right side elevational view of a bacteria filter or similar article showing my new design, with the opposite side being a mirror image;

FIG. 2 is a front elevational view thereof, with the rear being a mirror image;

FIG. 3 is a right side elevational view thereof, with the output port shown in alternate position; and,

FIG. 4 is a front elevational view thereof, with the output port shown in an alternate position.

FIG. 1

FIG. 2

FIG. 3

FIG. 4
